UNITED STATES PATENT OFFICE.

PAUL B. PARKS, OF OAK PARK, AND JOHN VAN VULPEN, OF CHICAGO, ILLINOIS, ASSIGNORS TO VAPOR CAR HEATING COMPANY, INC., OF CHICAGO, ILLINOIS, A CORPORATION OF NEW YORK.

HEATING SYSTEM.

Application filed May 19, 1923. Serial No. 640,133.

To all whom it may concern:

Be it known that we, PAUL B. PARKS and JOHN VAN VULPEN, citizens of the United States, residing at Oak Park, Illinois, and Chicago, Illinois, respectively, have invented certain new and useful Improvements in Heating Systems, of which the following is a specification.

Our invention relates to a steam heating system intended particularly for the heating of railway cars, and has for its object the provision of improvements in a heating system of this character, whereby two or more radiating coils and their valves may be connected in one circuit and to provide further improvements in the valves whereby any water delivered from the first coil to the valve of the second coil is discharged from the latter valve instead of being circulated with the steam through the second coil.

The invention consists of the new and improved constructions and arrangements and devices shown in the accompanying drawings, and to be hereinafter described and claimed for carrying out the above stated objects and such other incidental objects as will be mentioned in the following description of the preferred embodiments of the invention shown in the drawings.

We do not claim herein the features of the valve apart from the other instrumentalities of the heating system; the valve being claimed in a copending application filed April 18, 1924, Serial 707,435.

In the drawings,

Fig. 1 is a plan view with parts in section, in the nature of a diagram illustrating a heating system in which there are two radiators, and two radiator valves connected up in series.

Fig. 2 is a vertical sectional view on line 2-2 of Fig. 3.

Fig. 3 is a sectional plan taken through the valve, this figure being on a plan indicated by line 3-3 of Fig. 4.

Fig. 4 is a sectional view through the valve, showing a drainage passage for water of condensation.

Fig. 5 is a fragmentary plan view similar to that of Fig. 3, but showing the valve body in its closed position, instead of the open position shown in Fig. 3.

Fig. 6 is a detail vertical sectional view of the valve.

Fig. 7 is a fragmentary view, in perspective, of the lower portion of the stem for operating the rotary valve body of the radiator valve, and

Fig. 8 is a similar view of the top of the valve body.

The heating system herein shown consists preferably of a primary radiator A and a secondary radiator A', controlled by primary and secondary radiator valves B and B', respectively, so connected with each other, that the steam discharged from the primary coil A may be directed into the secondary coil A'.

Before describing the heating system as a whole, we will describe in detail the radiator valve construction. Both valves are preferably the same in construction. It will therefore be sufficient to describe the primary valve.

Radiator valve.—The radiator valve comprises a casing 50 divided by webs 51, 52, 53, 54, 55 and 56 (Figs. 3 and 5) into six chambers comprising a supply chamber a, a drip chamber e, a first return chamber f, an inlet chamber b, a second return chamber c, and a discharge chamber d, all of which are arranged around a central valve chamber containing a rotary valve body 57, the latter being composed of an upper disc 58, a lower disc 59 and vertical webs 60, 61 and 62, web 60 being reinforced by an enlargement 63, all of these separately enumerated parts of the valve body being preferably cast in a single integral structure. The lower disc 59 is formed with a stud 64 which enters a recess 65 in the bottom plate 66 of the valve casing 50. The upper disc 58 of the valve body is formed with a circular rib or boss 67 in which are cut diametrically arranged grooves 68, 69, the under surface of the latter being sloped, as indicated in Figs. 6 and 8. The valve casing is closed on the top by a bonnet 70 in which is fixed a gland 71. The operating stem 72 of the valve is

made separate from the valve body, extends through the bonnet 70 and gland 71 and is formed at its lower end with a transverse head 73 entering the grooves 68, 69 in the boss 67 on the top of the valve body, the end of the head 73 designed to fit the groove

69 being tapered as indicated at 74. By this arrangement the head is irreversible with respect to the valve body for the purpose of avoiding mistakes in assembling. 5 The under surface of the head 73 is formed with a projecting portion 75 to bear on a projecting portion 76 on the top of the valve body. By constructing the interengaging parts of the valve stem and body in this 10 manner a certain accommodation is provided which minimizes care in the assembly of the parts and facilitates the machining of such parts as require close fitting. With the valve stem integral or rigidly connected 15 with the valve body, it was a matter of difficulty to produce a valve of this type which would turn freely. The valve may be turned from one position to another by means of a lever F.

20 Arranged in the bonnet 70 against a conical surface 77 thereof is a packing ring 78, of smaller diameter than the space in which it is arranged, formed with its lower end conical to fit surface 77. In the upper end 25 of the gland 71 and arranged against a conical surface 79 thereof is a similar packing ring 80. A spiral spring 81 is interposed between washers 81^a bearing against the 30 packing rings 78, 80. The packing rings 78, 80 are made of smaller diameter than the spaces in which they are located so that they may expand when the valve is heated up 35 without interfering with the free rotary movement of the valve stem. The packing rings, in practice, turn with the valve stem. They are kept in sealing position against the bonnet 70 and gland 71 by the coiled spring 81. When wear takes place on the conical under surfaces of the packing rings 40 looseness is prevented by the take-up spring 81.

Referring now to the primary radiator of Fig. 1 and the valves of Figs. 3, 4 and 5, the course of the heating medium through the radiator A and valve B will be traced. 45 82 is a steam supply pipe leading to chamber a of valve B. This pipe may lead from the low pressure chamber of a vapor regulator of the type shown in the patent to Russell, 1,440,701, January 2, 1923. With the valve 50 in the open position (Fig. 3) the steam entering chamber a passes across the central valve chamber to chamber b, all of the other chambers of the valve casing being shut off from supply chamber a. From chamber b 55 the steam passes through coil 83 into a coil 84. The water of condensation in coil 83 passes down through a pipe 85 into chamber f of the valve. The bottom 66 of the valve casing is formed with a web 86 in which is 60 a duct 87 (Fig. 4) extending from a well 88 in the bottom of chamber f to a well 89 in chamber c. The water of condensation entering chamber f will flow through this duct and from chamber c across the central 65 valve chamber to chamber d. From this

chamber leads a discharge pipe 96 which connects valve B with valve B'. When the valve B is turned from its open position to its closed position, in Fig. 5, the steam and water of condensation will pass through the chambers a' and d' to the discharge pipe 90 and thence to the thermostat casing of the vapor regulator. The steam and water of condensation from coil 84 enters the chamber c from the return end 91 of coil 84 and from here passes out through chamber d and pipe 96 to valve B'. When the primary valve is turned from its open position, as shown in Fig. 3, to its closed position shown in Fig. 5, the steam entering the chamber a passes directly to chamber d and to a pipe 96. If the secondary valve be closed as above mentioned, the steam will pass through chamber a' to chamber d' and thence through the pipe 90 to the thermostat casing of the vapor regulator. Just enough steam will follow this course to keep the vapor regulator warm. The other four chambers of the valve are shut off from chambers a and d but are in communication with each other for the purpose of draining the coils 83, 84. The drip chamber e is connected by a duct 92 in the bottom of the casing with a nipple 93 arranged centrally of the valve casing and threaded for a discharge pipe (Fig. 2). Webs 61 and 62 of the valve body are in such position that chambers e, b and f are all open to the central valve chamber and the latter in communication with the discharge chamber e. 95 94 is a small drain opening from the valve chamber into duct 92 to prevent the collection of water in the valve chamber underneath the valve. The chambers b and f are formed with depressions 95, 95' which are preferably connected by drilling a duct 95.

When the secondary valve is in its open position, the steam passing from valve B to valve B' will be directed into the second radiator coil A', which coil is preferably the same in construction as radiator coil A. Unless some provision were made for separating the water from the steam and discharging the water at this point, the efficiency of the secondary radiator would obviously be considerably reduced. In fact, the efficiency of the entire system would be reduced because of the necessity of forcing water of condensation taken from the primary radiator through the secondary radiator. To remedy this difficulty the duct 95, 95', 95'', above referred to, has been provided between chambers b' and f'. When water and steam enter the chamber b' of the secondary valve the water passes from chamber b' to chamber f' through the duct just referred to, while the steam passes into the coil 83' and thence into coil 84'. The water of condensation from coil 83' enters cham- 120 125 130

ber f' , of the secondary valve, through pipe 85' and this water of condensation, together with the water of condensation entering chamber f' from duct 95, 95', 95'' passes through duct 87 to chamber c' and is then discharged to the vapor regulator through chamber d' and pipe 90, together with the water of condensation from the coil 84' of radiator A'.

- 10 In Fig. 1, the return pipes 85 and 91 are shown as connected with and discharging into one side of chambers f and c , whereas in Figs. 3 and 5, these pipes 85 and 91, are shown as discharging into a different side 15 of each of chambers f and c . Obviously the operation is the same in either case, and the construction of the valve casing may be varied in this manner to accommodate different types of car installations.
- 20 By this arrangement the radiating system is divided, effectively, into four independent circuits, independent in the sense that they discharge their water of condensation at four different points, but continuous in the 25 sense that each coil receives the steam discharged from the coil ahead of it. The employment of the duct 95 will be possible with the four-chambered valve used when the secondary radiator consists of a single 30 coil instead of two coils, as shown.

We claim:

1. In a heating system, the combination of two radiators and valves associated with said radiators, respectively, constructed and 35 connected so that steam may be introduced into one of said valves, circulated successively through said radiators and the water of condensation discharged from the other valve, said last named valve comprising a 40 casing having an outlet and a valve body which in one position directs the incoming steam to the radiator associated with said valve and the water of condensation from said radiator to said outlet, said casing being 45 formed with a water sealed duct arranged, when the valve body is in the position mentioned, to allow water of condensation entering the valve with steam from the other radiator to pass directly to the outlet 50 of said valve instead of circulating with the steam through the radiator associated with said valve.

2. In a heating system, the combination of two radiators and valves associated with 55 said radiators, respectively, constructed and connected so that steam may be introduced into one of said valves, circulated successively through said radiators and the water of condensation discharged from the other valve, said last named valve comprising a 60 casing having an outlet and a valve body which in one position directs the incoming steam to the radiator associated with said valve, and the water of condensation from 65 said radiator to said outlet, said valve be-

ing provided with means which, when the valve body is in the position mentioned, permits water entering said valve from the other radiator to pass directly to said outlet instead of being circulated with the steam 70 through the radiator associated with said valve while preventing the steam entering said valve from following the same course.

3. In a steam heating system, the combination of primary and secondary radiator valves, comprising, in each instance, a casing formed with supply, inlet, second return, and discharge chambers, and a valve body, which in one position puts the supply and inlet chambers into communication with each other, and in another position establishes communication between the supply and discharge chambers, a radiator associated with each of said valves, having its inlet end connected with the inlet chamber, 85 and its return end with the second return chamber, a steam supply pipe leading to the supply chamber of the primary valve, a pipe leading from the discharge chamber of the primary valve to a supply chamber of the 90 secondary valve, an outlet from the discharge chamber of the secondary valve, the secondary valve being formed with a water sealed duct between the inlet and second return chambers. 95

4. In a steam heating system, the combination of primary and secondary radiator valves, comprising in each instance, a casing formed with a central valve chamber, and a plurality of chambers arranged around the same including a supply chamber, an inlet chamber, a second return chamber, and a discharge chamber, and a rotary valve body in said valve chamber, which in one position puts the supply and inlet chambers into communication with each other, and in another position establishes communication between the supply and discharge chambers, a radiator associated with each of said valves, having its inlet end connected with the inlet chamber, and its return end with the second return chamber, a steam supply pipe leading to the supply chamber of the primary valve, a pipe leading from the discharge chamber of the primary valve to the supply chamber 100 of the secondary valve, an outlet from the discharge chamber of the secondary valve, the secondary valve being formed with a water sealed duct between the inlet chamber 105 and the second return chamber. 110

5. In a steam heating system, the combination of primary and secondary radiator valves, comprising, in each instance, a casing formed with a supply chamber, drip chamber, first return chamber, inlet chamber, second return chamber and discharge chamber, and a valve body, which in one position puts the supply chamber in communication with the inlet chamber, shutting off the other 125 chambers from the supply chamber, and in 130

another position shuts the inlet chamber from the supply chamber, and puts the discharge chamber in communication with the supply chamber, a radiator associated with each of said valves, having an inlet end connected with the inlet chamber and return ends connected with the first return and second return chambers, a steam supply pipe leading to the supply chamber of the primary valve, a pipe leading from the discharge chamber of the primary valve to the supply chamber of the secondary valve, an outlet from the discharge chamber of the secondary valve, the secondary valve being formed with a water sealed duct connecting the inlet chamber and second return chamber.

6. In a steam heating system, the combination of primary and secondary radiator valves comprising, in each instance, a casing formed with a supply chamber, a drip chamber, a first return chamber, an inlet chamber, a second return chamber, and a discharge chamber, and a valve body which in one position puts the supply chamber into communication with the inlet chamber, shutting off the other chambers from the supply chamber, and in another position puts the supply chamber into communication with the discharge chamber, and the second return, the inlet, and first return chambers into communication with the drip chamber, a radiator associated with each of said valves, having an inlet end connected with the inlet chamber, and return ends connected with the first return and second return chambers, a steam supply pipe leading to the supply chamber of the primary valve, a pipe leading from the discharge chamber of the primary valve to the supply chamber of the secondary valve, an outlet from the discharge chamber of the secondary valve, and drainage outlets from the drip chambers of both valves, each of said valves being formed with a water sealed duct from the first re-

turn chamber to the second return chamber, and the secondary valve being formed with a water sealed duct from the inlet chamber to the first return chamber.

7. In a heating system, the combination with a radiator having a drain outlet intermediate its inlet and discharge ends, of a valve for controlling the admission of steam to the radiator, comprising a casing formed with a supply chamber, an inlet chamber communicating with the inlet end of the radiator, a first return chamber communicating with the intermediate drain outlet of the radiator, a second return chamber communicating with the discharge end of the radiator, and a discharge chamber, and a valve body arranged in the casing and adapted in one position to direct steam into the radiator, and in another position to connect the supply and discharge chambers, the valve casing being formed with a fluid sealed duct between the first return and the second return chambers.

8. In a heating system, the combination with a radiator having a drainage outlet intermediate its inlet and discharge ends, of a valve for controlling the admission of steam to the radiator, comprising a casing formed with a supply chamber, an inlet chamber communicating with the inlet end of the radiator, a first return chamber communicating with the intermediate drainage outlet of the radiator, a second return chamber communicating with the discharge end of the radiator, and a discharge chamber, and a valve body arranged in the casing and adapted in one position to direct steam into the radiator, and in another position to connect the supply and discharge chambers, the valve casing being formed with a fluid sealed duct between the inlet chamber and the first return chamber.
